TICKET PUNCH

Hubert Chauncy Hart, Unionville, Conn.

Application November 22, 1939, Serial No. 305,719

4 Claims. (Cl. 164—121)

My invention relates to hand-operated ticket punches and aims to provide an improved device of this character which will be advantageous from standpoints of manufacture, sale, use and repair.

In carrying out the above end, a further object is to provide a novel die cooperable with the usual punch pin and detachably mounted to permit the substitution of a new die for the old die when the latter has become so worn that the tool will not cleanly punch.

A further object is to provide a novel arrangement of levers which will operate the punch pin with such force that unusually heavy cardboard or the like may be readily punched with ease.

With the foregoing in view, the invention resides in the novel subject matter hereinafter described and claimed, description being accomplished by reference to the accompanying drawing.

Figure 1 is a perspective view.

Figure 2 is a central vertical longitudinal sectional view.

Figure 3 is a perspective view of the die.

A preferred construction has been illustrated and will be rather specifically described, with the understanding, however, that within the scope of the invention as claimed, variations may be made.

An elongated one-piece lever 10 is provided, the front portion of said lever constituting the fixed jaw 11 of the punch, while the rear end is shaped to form a handle 12. The entire lever is preferably pressed or bent from one piece of sheet metal as shown, being given a longitudinally channeled formation. The vertical side flanges 13 project upwardly throughout the length of the lever and the portions of these flanges which project upwardly from the bottom plate 14 of the jaw 11, are denoted at 13'. This bottom plate 14 is also formed with an upwardly projecting front end flange 15 which merges into and is integrally joined to the side flanges 13'.

45 A pressed or stamped metal die plate 16 extends between the upper edges of the flanges 13', said die plate being provided with two downwardly projecting side flanges 17, with a downwardly projecting rear end flange 18, and preferably with a downwardly projecting front end flange 18', these various flanges being integrally joined to each other and being of the same height. The flanges 17 and 18 all rest upon the bottom plate 14 of the jaw 11, the two plates 14 and 16 and their flanges thus cooperating in forming a re-

ceiver 19 for punched-out pieces of material. The side flanges 17 of the die plate 16 lie against the inner sides of the flanges 13' of the jaw bottom plate 14 and when the flange 18' is employed, it lies against the inner side of the front end flange 15 of said bottom plate 14.

A discharge opening 20 is provided in the bottom plate 14 through which to empty the contents of the receiver 19, and a closure plate 21 is provided for said opening 20. In the present construction, a single screw 22 passes through the closure plate 21, the bottom plate 14 and the die plate 16 to detachably secure the entire die to the jaw 11 and at the same time form a pivot for the plate 21, permitting the latter to be swung aside when the opening 20 is to be uncovered.

The die plate 16 is provided with an opening 23 cooperable with a suitable punch pin 24 carried by the front end portion or jaw 25 of a relatively short lever 26. This lever is preferably pressed or stamped from sheet metal, is received between the flanges 13 of the lever 10, and is fulcrumed between its ends at 27 to said flanges. The side flanges 28 of the short lever 25 project downwardly and they are preferably provided with slots 29 through which a stop pin 30 passes to limit the swinging movements of said lever 26, said stop pin 30 extending through openings in the flanges 13 and having its ends 30 upset. The fulcrum 27 may also be fastened in this same manner.

A handle lever 31 is fulcrumed at its front end to the rear end of the short lever 26, as denoted at 32, said handle lever 31 being preferably stamped or pressed from sheet metal and having a longitudinally channeled form with its side flanges 33 extending toward the lever 10. The fulcrum 32 passes through the side flanges 28 of the short lever 26 and through the side flanges 33 of lever 31 and the ends of said pin are suitably upset.

A roller 34 is mounted on the handle lever 31 near its front end, said roller in the present disclosure being received between the flanges 33 and mounted on a pivot pin 35 which passes through openings in said flanges and has its ends upset. When lever 31 is swung toward the handle 12, the roller 34 rolls forwardly upon the bottom portion 36 of the channeled lever 10, causing said lever 31 to pry the rear end of the short lever 26 away from said bottom portion 36, thus moving the jaw 25 toward the jaw 11 to drive the punch pin 24 through the material being punched and into the opening 23. Each 55

time the punch is operated, the punched-out piece of material is received in the receiver 19, and when the contents of this receiver are to be discharged, it is a simple matter to swing the plate 21 aside, exposing the opening 20. Whenever the edges of the opening 23 become so worn that the punch will not cleanly cut, it is an easy matter to remove the entire die plate 16 and substitute another, prolonging the life of the tool.

Any suitable provision may be made to insure the opening of the punch when pressure upon the handles is relieved, and for this purpose, I have illustrated a spring 37 which extends over the fulcrum pin 21, under the stop pin 30, and is riveted at 38 to the bottom portion 36 of the lever 10 at its rear end, the front portion of said spring being simply free and confined between the side flanges 28 of the short lever 26.

If desired, the opening 23 may be threaded as shown, spaced the same distance from the front end of the die plate 16 that the screw hole 39, for screw 22, is spaced from the rear end of said die plate, and of the same diameter as said screw hole 39. Thus, instead of substituting a new die when opening 23 will no longer coact effectively with pin 23, the old die plate may simply be removed and reversed, positioning the hole 39 for coaction with said pin and allowing reception of the screw 22 in the opening 23.

Excellent results have been obtained from the details shown and described, and they are, therefore, preferably followed. However, within the scope of the invention as claimed, variations may be made.

I claim:

1. In a punch, a lower jaw provided with a bottom plate, said bottom plate having upwardly projecting vertical side flanges and a vertical upwardly projecting front end flange, a die plate having downwardly projecting vertical side flanges and at least a downwardly projecting rear end flange, said side flanges of said die plate contacting with the inner sides of said side flanges of said bottom plate, all of said flanges of said die plate resting on said bottom plate, whereby the two plates and their flanges coact in forming a receiving casing for punched-out pieces of material, said die plate having an opening to receive a punch pin, said bottom plate having an opening through which to discharge the contents

of said receiver, a closure for said discharge opening, and means detachably securing said plate and flanges in assembled relation.

2. In a punch, a lower jaw provided with a bottom plate, said bottom plate having upwardly projecting vertical side flanges and a vertical upwardly projecting front end flange, a die plate having downwardly projecting vertical side flanges and at least a downwardly projecting rear end flange, said side flanges of said die plate contacting with the inner sides of said side flanges of said bottom plate, all of said flanges of said die plate resting on said bottom plate, whereby the two plates and their flanges coact in forming a receiving casing for punched-out pieces of material, said die plate having an opening to receive a punch pin, said bottom plate having an opening through which to discharge the contents of said receiver, a closure plate contacting with the lower side of said bottom plate for closing said discharge opening, and a fastener passing through said closure plate, said bottom plate and said die plate, said fastener securing said die plate removably in position and also constituting a pivot for said closure plate.

3. A punch or similar tool comprising a relatively long lever having a jaw at its front end and a handle at its rear end, a relatively short lever fulcrumed between its ends to said long lever and having a jaw at its front end, a handle lever fulcrumed at its front end to the rear end of said short lever, and a roller mounted on the front portion of said handle lever to roll forwardly on said long lever and pry the rear end of said short lever away from said long lever when said handle lever is forced toward the aforesaid handle.

4. In a punch having two relatively movable jaws and a punch pin secured to one of said jaws; a reversible die contacting with the other of said jaws and having two openings of the same diameter with their axes parallel, one of said openings being cooperable with said punch pin, and a removable fastener engaged with the other of said openings and said other jaw and securing said die to said other jaw, whereby said fastener may be removed, the die reversed to interchange the positions of the two openings, and the fastener reinserted.

HUBERT CHAUNCY HART.
